FLAW DETECTOR CARRIAGE

Walter C. Barnes, Lake Bluff, and John C. Dionne,
Chicago, Ill.

Application February 18, 1950, Serial No. 144,946

20 Claims. (Cl. 175—183)

1

This invention relates to improvements in apparatus for magnetically detecting rail flaws such as fissures. The general principle in accordance with which such apparatus operates is that if a rail be properly subjected to moving magnetic fields, the fissures can be polarized and then detected by suitable apparatus responsive to the residual magnetic conditions in the vicinity of the polarized flaws.

The present invention is not concerned with the details of construction and mode of operation of the electrical apparatus and circuits pertaining thereto, but rather with the mechanical structure of the detector carriage employed for supporting and positioning with respect to the rails, one of the energizing magnets and the pick-up portions of the detector apparatus.

When the car carrying the apparatus moves along a track whose rails vary in curvature, elevation and general straightness, some adequate means is required which shall be able automatically to respond to track variations in order to obtain and maintain proper and uniform application of the magnetic fields to the rails and maintain the pick-up devices properly aligned.

It is to this problem that this invention is primarily devoted, although other objects and advantages of this invention will become apparent from the following specification in which a preferred form of the invention is shown and described.

In the drawings:

Fig. 1 is a side elevational view showing a portion of the detector carriage of the present invention, associated with one rail only, and designed for attachment to the underside of a test car;

Fig. 2 is a top plan view of a portion of mechanism shown in Fig. 1;

Fig. 3 is an end elevation of the carriage, showing it associated with a pair of rails;

Fig. 4 is a side elevational view of the pickup box at the end of the carriage; and

Fig. 5 is an end elevation of the same box.

The drawings accompanying this specification, and the description which follows, disclose a preferred embodiment of the invention as required by Section 4883 of the Revised Statutes, but the invention is not limited to the embodiment chosen for illustration, and the appended claims should be construed as broadly as the prior art will permit.

The detector carriage herein disclosed may be mounted on test cars of various designs, but for practical reasons has been adopted especially for mounting on test cars already in use. The floor

of such a car is herein designated as 20, to the underside of which may be secured standard longitudinal channel beams 21, 22, 23 and 24, and brackets such as 25 and 26.

5 To the brackets 25 and 26 are bolted rigid depending T bars 27 and 28, to which are attached short chains 29 and 30, the chains being connected to clevis 31 and pin 32 connected to the rear and front end portions, respectively, of 10 the main carriage bar 33. If desired the main carriage bar may be made of aluminum to save weight, and to it, directly or indirectly, all the other carriage parts may be attached.

A sub-carriage bar 34 is supported on the rail 15 by wear shoes 35 and 36, preferably made of stainless steel. To the rear end of the bar 34 is bolted a split head pickup box 37, having a hanger bracket 38 slotted at 39 to permit adjusting the box vertically to maintain a desired clearance above the top surface of the rail represented by the line 40.

20 A cross magnet 41 straddles and is supported on bar 34 at a fixed distance forwardly of the pickup box 37 in a manner to cause it to ride at 25 a constant air gap above the rail.

The details of construction of the pickup box and cross magnet do not form a part of this invention; hence will not be described any further than as here stated to show their relative positions and means of support.

30 The main carriage bar 33 is supported on replaceable shoes 42 and 43, which are clamped by means of brackets 44 and bolts 45 to horizontal support bars 46 and 47, which in turn are 35 rigidly secured to the carriage bar 33 by vertical bolts, such as 48, which clamp the bars 46 and 47 against vertical spacing plates, such as 49 and 50.

When the entire carriage is raised from the track the bar 34 will ride on bar 46, but when the 40 apparatus is in testing position there will be clearance between the top of bar 34 and the underside of bar 33, and clearance between the underside of bar 34 and the top of bar 46.

As shown in Fig. 1, one or a pair of links 51 45 pivotally connected to the front end of bar 34 and to a bracket 52 secured to main carriage bar 33 serves to tow the sub-carriage bar 34, and at the same time exert a lifting force on the sub-carriage which tends to shift some of the weight 50 of the sub-carriage assembly from shoe 36 to shoe 42. The wearing capacity of shoe 42 will preferably exceed that of shoe 36, and it is contemplated that if shoe 42 should wear faster, perhaps due to the above-mentioned shifting of 55 weight, the main carriage beam 33 will eventually

rest upon the top of sub-carriage bar 34 and thus redistribute the weight. It is the purpose to have all three shoes wear to replacement condition together as a matter of maintenance convenience.

The maintenance of a desired air gap between cross magnet 41 and the rail, as shoe 36 wears thinner, can be regulated by the insertion of shims between the magnet and its resting place on bar 34.

The gauge runners 53 are separate pieces which, as shown, may conveniently be bolted to the shoe support bars 46 and 47, and are thus readily replaceable independently. These runners serve to hold the main carriage tracking parallel with the rail, while a gauging pressure mechanism, later described, maintains them against the inner sides of the rail heads.

A main pickup box 54 is carried by the main carriage beam 33 upon vertically adjustable threaded parts, such as 55, to which are adjustably secured, as shown, hanger brackets, such as 56, the latter being connected to angle brackets 57 fixed upon the top of the pickup box.

The box 54 has a replaceable wear shoe 58, which enables it to ride directly on the rail, if desired, and a depending side flange 59. Some vertical movement of the pickup box and beam 33 is provided for by having the bolts, such as 60, pass through vertically extending slots either in brackets 56 or 57 and adjusting the threaded pins 55 from time to time so that these bolts 60 will, on the average, ride about midway in these slots.

Having this means of mounting, the pickup box 54 is readily lifted over stepped rail ends by the rail shoe 43, and by reason of its support on the bolts 60 it may tilt about a longitudinal axis to maintain parallelism with the top of the rail.

In some cases it will be preferable to have the pickup box 54 mounted out of engagement with the rail, and this can easily be done by proper adjustment of the bolts 55 and 60.

When the carriage assembly is raised from the track during a non-testing period the chains 29 and 30, though inclined upwardly, assist in maintaining the carriage parallel to the track.

Fig. 3 shows a pair of rails 61 and 62 and a detector carriage in test contact with each rail. To maintain these carriages vertically, or nearly so, while in testing position a horizontal link 63 is pivotally connected to channel beam 22 and to a vertical link 64, the lower end of which is pivotally connected at 65 to a bracket 66 affixed in any suitable manner to the top of carriage beam 33. Utilizing a slot 67 in bracket 66 and a bolt 68 passing therethrough, the link 64 may be adjustably but rigidly so connected to the carriage as to maintain the latter in a substantially vertical position when in testing contact with the rail.

Links identical with 63 and 64 for the same purpose are connected with the carriage positioned on rail 62, but are omitted from the drawing for clarity.

Automatic gauging

For automatic gauging, or adjustment of the carriages to track variations, the following mechanism is provided:

A bracket 69 is rigidly secured in any appropriate manner to the underside of the test car, and to this is rigidly secured the inclined bracket 70 on which is pivotally supported at 71 a lever 72. Rigidly affixed to the upper end of lever 72

is an arm 73 on which is rigidly mounted a weight 74 spaced far enough from floor beam 21 to clear it under all conditions.

A turnbuckle rod 75, oppositely threaded at its ends, is pivotally connected by threaded sleeves 76 and 77 to the lower end of lever 72 and to a bracket 78 rigidly secured to the carriage beam.

A rigid link 79 is pivotally connected to lever 72 and to a pendulum rod 80 which is pivotally suspended from bracket 81 and carries on its lower end a vertically adjustable weight 82. It will be recognized that weight 74 not being located vertically above the pivot 71, tends to disturb the equilibrium of the linkage system just described, but this is compensated for by normally having pendulum 80 slightly displaced to the right of its true vertical position to re-establish equilibrium.

As the linkage system connected to the right hand carriage in Fig. 3 is obviously the same, but reversely disposed, as that just described in reference to the left hand carriage, additional reference numerals are generally omitted for the sake of simplicity.

Tension springs 83 and 84, termed gauging springs, are connected at 85 to a bracket 86 and to the pendulum 80 and the corresponding pendulum 80' associated with the right hand carriage.

When the track is level and its gauge is exactly standard, the pendulum rods 72 and 80 will be substantially vertical and the pull of the gauging springs will tend to swing inner pendulum 80 and its counterpart 80' toward the track center, which force acting through the outer pendulum lever 72 and its counterpart serves to press the gauge runners, such as 53, against the gauge sides of the two rails.

While Fig. 3 and the description indicate for simplicity that there are only two pendulums and one tension spring connected with each carriage, in actual practice preferably a pair of pendulums and a spring are connected with each end of each carriage.

Assuming that the test car equipped with this apparatus is proceeding around a curve and that rail 61, being the outer rail, is higher than the inner rail 62 by about six inches, for example, under such conditions the body of the test car is tilted to the right, as Fig. 3 is viewed, and the left hand detector carriage would have a tendency to move toward the track center because of gravity. The pendulum 80 is displaced from its normal substantially perpendicular position, and while it is so displaced tends to act through link 79, and the pivotally supported inverted pendulum lever 72 exerts a force tending to pull the left hand carriage back toward the rail and to cause its gauge runners 53 to hug the rail side. The inverted pendulum 72-73-74 also being displaced from normal by the tilting of the car exerts an increased force in a manner to assist pendulum 80. Hence, the two pendulums under the conditions of track elevation compensate for the carriage's gravitational pull to the right.

While pendulum 80' tends also to shift to the right and such movement tends to shift the right hand carriage toward the track center, the gauging spring 84 and the right hand inverted pendulum exert a counteracting force which is adequate to hold the gauge runners to the right hand carriage against the track side. The right hand carriage will naturally tend of its own weight to hug the rail.

Another factor tending to hold the left hand

carriage on the higher rail, flanging against that rail is that due to the curvature of the track the wheels of the test car tend to flange against the high side rail. Thus all the flanging clearance on the high side is removed and the tow chain 30 and the trailing chain 29 assist in positioning the high side carriage outwardly from the track center, and this would be true whether the carriage were in testing or raised position. The combined effect of this factor and the pendulum compensation is designed to compensate for the carriage's tendency to fall away from the high side rail.

When the test car is riding on level straight trackage the shape of the wheels tends to cause the car to ride midway between the rails, and the pendulum system under these conditions is designed to be generally in what may be termed as perpendicular equilibrium on the non-elevated track. However, of necessity, there must be some side clearance between the wheel flanges and the rails, and this clearance will vary due to wear and may show up on either side. On level straight track there is, therefore, frequent lateral or "nosing" movement between the car and the rails.

Since each detector carriage should remain laterally constant with its rail there is lateral movement between each carriage and the test car, and such lateral movement will disturb the perpendicular equilibrium of the pendulum system. In the absence of track elevation the carriage does not counteract this relative displacement when the car noses to one side or the other.

Assuming that the car noses to the right, as Fig. 3 is viewed, this means that with respect to brace 69 the track moves to the left. The automatic gauging mechanism is exerting gauging pressure against rail 61 and causes the left hand carriage to tend to follow the rail. This movement is accomplished principally by the gauging spring 83, for it is apparent that as the carriage shifts to the left the weight 74 on the inverted pendulum tends to shift to the right exerting a force to the right on link 79 while pendulum 80 tends to exert a force to the left on link 79, the one force canceling the other force sufficiently so that the gauging spring 83 retains major control over the gauging force.

Whichever way the car noses the compensatory forces in the gauging mechanism associated with each carriage will act correctively and quickly and maintain each carriage gauging properly on its rail.

Fig. 3 shows two lifting tables or chains 87 and 88, each connected to an eye bolt, such as 89, secured to the upper side of each main carriage beam 33. Some suitable source of power (not shown) is employed to lift these cables to raise both carriages a few inches above the rails when the car is running but not testing. The pulleys 90 and 91 are mounted on the car body in any suitable manner (not shown) somewhat inwardly of the rails, hence the lifting force of the cables (which are slack during testing) draw the carriages inwardly and upwardly, and this inward movement is aided by the pivotal movement of turnbuckle rods, such as 75. This inward movement of the carriages when being raised is desirable, so that when they are subsequently being lowered the gauge runners will be certain to gauge against the inner sides of the rail heads rather than ride on the top of the rails.

It will now be appreciated that the apparatus herein shown and described assures the proper

alignment of the testing devices with the rails during testing, and that automatic gauging is readily accomplished as the test car moves along the track.

We claim:

1. In a rail flaw detection apparatus for attachment to a test car, a detector carriage adapted in testing position to ride upon a rail and having a gauge runner, a pair of pendulums pivotally mountable on the car, means connecting said pendulums to effect simultaneous opposite angular rotation of the two about their pivots responsive to gravitational forces, and means controlled by the rotation of said pendulums for controlling the gauging position of said runner.
2. In a rail flaw detection apparatus for attachment to a test car, a detector carriage adapted in testing position to ride upon a rail and having a gauge runner, a pair of pendulums pivotally mountable on the car inwardly and outwardly of the rail position of the carriage, and means operatively connecting said pendulums to said carriage for gravitationally effecting control upon the gauging position of said runner.
3. In a rail flaw detection apparatus for attachment to a test car, a detector carriage adapted in testing position to ride upon a rail and having a gauge runner, a pair of pendulums pivotally mountable on the car inwardly and outwardly of the rail position of the carriage, and means linking said pendulums to said carriage for gravitationally regulating the gauging position of said runner.
4. In a rail flaw detection apparatus for attachment to a test car, a detector carriage adapted in testing position to ride upon a rail and having a gauge runner, an arm connected with the carriage, and a pair of pendulums linked to said arm and pivotally mountable on the car inwardly and outwardly of the rail position of the carriage gravitationally acting on said arm for regulating the gauging of said runner against the inner side of the rail.
5. In a rail flaw detection apparatus for attachment to a test car, a detector carriage adapted in testing position to ride upon a rail and having a gauge runner, an inverted pendulum and a normal depending pendulum pivotally mountable on the car, and means connecting said pendulums to said carriage for controlling the gauging position of said runner.
6. In a rail flaw detection apparatus for attachment to a test car, a detector carriage adapted in testing position to ride upon a rail and having a gauge runner, an inverted pendulum and a normal depending pendulum pivotally mountable on the car, and means connecting said pendulums to said carriage for controlling the gauging position of said runner, and a tension spring connectable to the car and acting on one of said pendulums in opposition to the gravitational force thereon.
7. In a rail flaw detection apparatus for attachment to a test car, a detector carriage adapted in testing position to ride upon a rail and having a gauge runner, weight carrying arms pivotally mountable on the car, means linking said arms together to effect a generally perpendicular equilibrium between the rotative forces produced by said weights, and means connecting one of said arms with said carriage for controlling the gauging position of said runner.
8. In a rail flaw detection apparatus for attachment to a test car, a detector carriage

adapted in testing position to ride upon a rail and having a gauge runner, weight carrying arms pivotally mountable on the car, means linking said arms together to effect a generally perpendicular equilibrium between the rotative forces produced by said weights, means connecting one of said arms with said carriage for controlling the gauging position of said runner, and a tension spring connectable with the car and operatively connected with the pendulum system for effecting additional gauging control on said runner.

9. In a rail flaw detection apparatus for attachment to a test car, a detector carriage adapted in testing position to ride upon a rail and having a gauge runner, a pendulum pivotally connectable at its upper end to the car, a second pendulum pivotally supported upon said car at a substantial distance below the pivotal support of the first pendulum, means pivotally connecting said pendulums for effecting simultaneous rotation of them in opposite angular directions when subject to gravitational displacement forces, and means controlled by the rotation of said pendulums for regulating the gauging position of said runner.

10. In a rail flaw detection apparatus for attachment to a test car, a detector carriage comprising a main carriage beam, fore-and-aft gauging shoes connected to said beam, a sub-carriage beam straddling one of said shoes longitudinally and vertically shiftable relatively to said main carriage beam, a detection magnet mounted on the forward part of said sub-carriage beam and a pickup device mounted on the rear part of said beam, track shoes supporting the sub-carriage beam upon a rail, and towing means connecting the sub-carriage beam to the main beam.

11. In a rail flaw detection apparatus for attachment to a test car, a detector carriage comprising a main carriage beam, means flexibly connecting said beam to the test car, gauging shoes secured to said main beam, a sub-carriage beam longitudinally straddling one of said shoes and vertically shiftable between said shoe and the main beam, track shoes supporting the front and rear end of said sub-carriage beam, a flaw detection magnet supported on the forward end of said sub-carriage beam, an electrical pickup device supported on the rear end portion of said sub-carriage beam, and means connecting the sub-carriage beam to the main carriage beam to effect towing of the former by the latter.

12. In a rail flaw detection apparatus for attachment to a test car, a detector carriage adapted in testing position to ride upon a rail and having a gauge runner, a pendulum for pivotal mounting on the car and normally depending therefrom in a substantially vertical position, a second pendulum, means for pivotally supporting the same upon the car in inverted position, means connecting said pendulums for simultaneous rotation in opposite angular directions, and means connecting one of said pendulums to the carriage for controlling the gauging position of said runner.

13. In a rail flaw detection apparatus for attachment to a test car, a detector carriage adapted in testing position to ride upon a rail and having a gauge runner, a pendulum and means for mounting the same in a substantially vertical depending position upon said car inwardly of the rail position of said carriage, a second pendulum and means for pivotally mounting the same in inverted position upon the car outwardly of the rail position of the carriage, the second pendulum having a weight positioned above and inwardly of its pivotal support, means connecting said pendulums whereby the rotation of one effects op-

ing the same in inverted position upon the car outwardly of the rail position of the carriage, means connecting said pendulums whereby the rotation of one effects opposite angular rotation of the other, and means connecting the inverted pendulum to the carriage for effecting an increased outwardly acting gauging force on said carriage upon movement of the first pendulum inwardly toward the track center.

14. In a rail flaw detection apparatus for mounting on a test car, a detector carriage adapted in testing position to ride upon a rail and having a gauge runner, linkage means pivotally connected with the test car for maintaining the carriage in vertical position while testing, a depending pendulum pivotally mountable on the car inwardly of the testing position of the carriage, an inverted pendulum pivotally mountable on the car outwardly of the testing position of the carriage, means connecting said pendulums for effecting simultaneous opposite angular rotation of them when subjected to gravitational displacement forces, means pivotally connecting one of said pendulums to the carriage for effecting pendulum control of the gauging position of the carriage runner, the axes of all aforesaid pivotal connections being disposed longitudinally relatively to the test car, and means for lifting the carriage from testing position arranged for effecting swinging movement of the carriage inwardly and upwardly from its testing position.

15. In a rail flaw detection apparatus, a car, a detector carriage adapted in testing position to ride upon a rail and having a gauge runner, and weighted gravity operated means pivotally supported on the car and operatively connected to the carriage for positioning said gauge runner, said means having a normal equilibrium position when the car is level and moving without side sway for exerting a predetermined normal positioning force upon said carriage for controlling the gauging of said runner, said means being gravitationally rockable out of equilibrium position when the car assumes a transversely tilted position for exerting a different positioning force upon said carriage.

16. In a rail flaw detection apparatus, a car, a detector carriage adapted in testing position to ride upon a rail and having a gauge runner, means pivotally connected to the car and carriage maintaining the carriage perpendicular to the car when testing, a gauging arm connected to the carriage for pulling the gauge runner against the rail, a lever pivotally supported on the car outside the rail position connected to said arm, a vertically depending lever pivotally supported on the car inside the rail position, a link extending above the carriage pivotally connecting the two levers, and resilient biasing means connected to the car and the second lever operative for resiliently biasing said gauge runner against the rail.

17. In a rail flaw detection apparatus for attachment to a test car, a detector carriage adapted in testing position to ride upon a rail and having a gauge runner, a pendulum and means for mounting the same in a substantially vertical depending position upon said car inwardly of the rail position of said carriage, a second pendulum and means for pivotally mounting the same in inverted position upon the car outwardly of the rail position of the carriage, the second pendulum having a weight positioned above and inwardly of its pivotal support, means connecting said pendulums whereby the rotation of one effects op-

posite angular rotation of the other, and means connecting the inverted pendulum to the carriage for effecting an increased outwardly acting gauging force on said carriage upon movement of the first pendulum inwardly toward the track center.

18. In a rail flaw detection apparatus for attachment to a test car, a detector carriage adapted in testing position to ride upon a rail and having a gauge runner, a pendulum for pivotal mounting on the car and normally depending therefrom in a substantially vertical position, a second pendulum and means for pivotally supporting the same upon the car in inverted position, means connecting said pendulums for simultaneous rotation in opposite angular directions, means independent of the pendulums for maintaining the carriage perpendicular to the rail, and means connecting one of said pendulums to the carriage for controlling the gauging position of said runner.

19. In a rail flaw detection apparatus for attachment to a test car, a detector carriage adapted in testing position to ride upon a rail and having a gauge runner, a pair of pendulums pivotally mountable on the car, means connecting said pendulums to effect simultaneous opposite angular rotation of the two about their pivots responsive to gravitational forces, means controlled by the rotation of said pendulums for controlling the gauging position of said runner, and resilient biasing means connected to one of

the pendulums to bias it to increase gauging pressure on said runner.

20. In a rail flaw detection apparatus, a car, a detector carriage adapted in testing position to ride upon a rail and having a gauge runner, means connected to the carriage and pivotally connected to the car maintaining the carriage substantially perpendicular to the rail when testing, a pendulum pivotally depending from the car inside the rail position, an inverted pendulum pivotally supported on the car outside the rail position having a weight inwardly offset above its pivot, a gauging arm connecting the lower end of the inverted pendulum to the carriage to effect an outward pull thereon, and a link pivotally connecting the two pendulums effecting a substantial equilibrium between their opposite angular rotative forces when the car is level for holding the gauge runner against the rail.
